[57] CLAIM

The ornamental design for a combined lavatory and vanity, as shown and described.

DESCRIPTION

FIG. 1 is a perspective view taken from the front of a combined lavatory and vanity showing our new design; FIG. 2 is a right side elevational view thereof, the left side elevational view being a mirror image thereof; FIG. 3 is a top plan view thereof;

FIG. 4 is an enlarged front elevational view thereof; FIG. 5 is a front elevational view of a second embodiment thereof;

FIG. 6 is a front elevational view of FIG. 4; and, FIG. 7 is another front elevational view of FIG. 4.

The fragmentary broken line representation of a bathroom wall in FIG. 1 and the broken line representation of a shroud in FIG. 6 and a pedestal in FIG. 7 are for purposes of illustration only and form no part of the claimed design.

FIG. 1

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 338,949
DATED : August 31, 1993
INVENTOR(S) Pierre H. Paulin, et. al.

It is certified that error appears in the above-identified patent and that said Letters Patent is hereby corrected as shown below:

On the Title page, item [56], under Other Publications, col. 2, line 14, after "advertisement" "for" should be --from--.

Column 2, line 19 of the Title page, under Other Publications, after "undated" --page 12 of an advertisement from Arte entitled "Kollektion System", undated should be added--.

Drawings:

Fig. 4, before "front", enlarged should be deleted--.

Signed and Sealed this
Fifteenth Day of March, 1994
